(57) CLAIM

The ornamental design for a pocket, as shown and described.

DESCRIPTION

FIG. 1 is a front, left side perspective view of a pocket showing my new design;

FIG. 2 is a front, right side perspective view thereof;

FIG. 3 is a rear, right side perspective view thereof;

FIG. 4 is a front, right side perspective view thereof;

FIG. 5 is a front, right side, bottom perspective view thereof; and,

FIG. 6 is a front, bottom perspective view thereof.

The pocket is comprised of flexible material and is therefore shown in different configurations in each of FIGS. 1-6. The short dashed broken lines in the Figures show stitching and form part of the claimed design. The longer dashed broken lines on the two zipper pulls show portions of the pocket that form no part of the claimed design. While the claimed design shown in FIGS. 1-6 shows a "left-hand" version of the pocket, it should be understood that a "right-hand" version of the pocket that is a mirror image of the design shown in FIGS. 1-6 is considered to be part of the claimed design.
